UNITED STATES PATENT OFFICE.

ALBERT F. FIFIELD, OF NEWARK, NEW JERSEY, ASSIGNOR TO THE SINGER MANUFACTURING COMPANY, OF ELIZABETH, NEW JERSEY, A CORPORATION OF NEW JERSEY.

THREAD-CONTROLLING DEVICE.

Application filed September 2, 1920. Serial No. 407,623.

To all whom it may concern:

Be it known that I, ALBERT F. FIFIELD, a citizen of the United States, residing at Newark, in the county of Essex and State of New Jersey, have invented certain new and useful Improvements in Thread-Controlling Devices, of which the following is a specification, reference being had therein to the accompanying drawings.

This invention relates to a thread-controlling device for sewing machines, its object being to prevent breakage of the thread, and comprises a yieldable thread-guide acting as a safety device to prevent breakage of the thread should an abnormal pull be imparted thereto.

It consists preferably of a yieldable guide which may be located between the tension device and the take-up and so arranged that under normal operation it acts merely as a stationary guide, but should an abnormal pull be placed on the thread the guide will yield giving up enough thread to prevent abnormal tension and so prevent breaking of the thread.

Reference is made to the accompanying drawings in which Fig. 1 shows a portion of the overhanging bracket arm of a sewing machine with my device applied thereto. Fig. 2 is a sectional elevation of my yieldable thread-guide. Figs. 3 and 4 are sections on the lines 3-3 and 4-4, respectively, of Fig. 1 and Fig. 5 is an elevation of the device illustrating its action when an abnormal strain is imparted to the thread.

Reference numeral 1 indicates the overhanging bracket-arm of the machine in the head of which is mounted for vertical reciprocation the needle-bar 2 provided at its upper end with a needle-thread take-up 3. Secured upon the upper portion of the bracket 1 by a suitable support 4 is the constant tension device 5 and also pivoted to this bracket or support 4 is the presser-bar lifting lever 6.

Between the constant tension device 5 and the needle-thread take-up 3 is secured a yieldable thread-guide which comprises a post 7 adjustably secured in a socket in the bracket-arm 1 by means of a set-screw 8, said post being provided with a flat side 8' for the end of the set-screw. The post is provided with a transverse slot 9 extending therethrough, and secured upon the post by

means of a pin 10 is a collar 11 which is cut away at 12 in alignment with the transverse slot 9 to provide on opposite sides of the post upwardly extending portions 13. Also mounted upon the post and adapted to freely slide thereon is the collar 14 provided with a reduced portion embraced by the coil spring 15. The upper end of the spring 15 abuts against a collar 16 adjustably mounted upon the upper end of the post 7 by means of a set-screw 17, the post being also provided at this end with a flat portion 17' forming a seat for the end of this screw.

A thread 7 is led from the supply through a guide 17" to the constant tension device 70 5 then under the lower end of the collar 14 through the slot 9 and at substantially right angles over the take-up 3 through the guide 18 to the needle. It will be noted that the raised portions 13 of the collar 11 serve to 75 space the end of the collar 14 from the lower end of the slot 9 allowing free passage of the thread through the slot under the collar 14. The spring 15 is normally under sufficient tension that it will not yield 80 during normal stitching operation being of sufficient strength to allow the take-up 3 to pull thread through the tension 5 without yielding and thus under normal operation acts merely as a stationary guide. If, however, the strain on the thread should become 85 abnormal the spring 15 will yield allowing the collar 14 to rise, as shown in Fig. 5, giving up sufficient thread to compensate for the increased tension thereon and thus 90 preventing breaking thereof.

It will be seen that my device forms a safety attachment for the thread of simple construction, inexpensive to manufacture and occupies very little space upon the head 95 of the machine and effectively prevents breakage of the thread should it be subjected to an undue pull.

Having thus set forth the nature of the invention, what I claim herein is—

1. In a sewing machine having stitch-forming mechanism including a needle, a tension device, a thread take-up, and a yieldable guide for the thread stronger than the tension device and located between the tension device and the needle, whereby said guide will be unyielding during normal operation of the machine but will yield and give up thread should an abnormal pull be applied to the thread.

2. In a sewing machine, a thread-tension device, a thread take-up, a yieldable thread-guide between the tension and the needle comprising a post having a transverse slot, a collar secured to the post and cut away on opposite sides in alignment with the slot leaving raised portions, a second collar freely slideable on said post, a spring tending to hold the second collar against the raised portions, the thread being led from the tension through the slot between the two collars and then at substantially right angles to the take-up.
3. In a sewing machine having stitch-forming mechanism, a constant tension device, a thread take-up, and a yieldable guide for the thread between the tension device and the needle comprising a post provided with a transverse slot, a collar secured to the post and having extensions on opposite sides of the slot, a second collar freely slideable on the post and adapted to rest on the free ends of the extensions on the first collar, a third adjustable collar on said post, and a coil spring between the second and third collars of sufficient tension to prevent yielding under the normal pull applied to the thread.
4. A yielding thread-guide for sewing machines comprising a post provided with a transverse slot extending therethrough, a stop on the post intermediate the ends of the slot, a collar freely slideable on the post, a spring mounted on the post and tending to

urge the collar against said stop, and means for adjusting the tension of the spring.

5. A sewing machine having stitch-forming mechanism including a reciprocating needle-bar carrying a needle, a tension device, a take-up thread-guide carried by the needle-bar, and a thread-guide intermediate the needle-bar and the tension device, said last-mentioned thread-guide comprising pressure exerting and pressure sustaining members, at least one of which is cut away to avoid nipping the thread passing intermediate said members, the pressure exerting member being stronger than the tension device.

6. In a sewing machine having a bracket-arm, the combination with a reciprocating needle-bar having a take-up thread-guide, and a tension device, of a cooperative thread-guide comprising a slotted post mounted on the bracket-arm of the machine to engage the thread between the needle-bar and tension device, a coil spring surrounding the post and at its lower end adapted to exert a downward pressure of predetermined intensity, and means independent of the thread for sustaining said pressure, whereby the thread will not be nipped, said spring being adapted to yield to the thread only under an abnormal pull.

In testimony whereof, I have signed my name to this specification

ALBERT F. FIFIELD.
